HERRMANN CRAMER, OF SONORA, CALIFORNIA.

Letters Patent No. 94,287, dated August 31, 1869.

IMPROVEMENT IN WASHING-MACHINES.

The Schedule referred to in these Letters Patent and making part of the same.

To all whom it may concern:

Be it known that I, HERRMANN CRAMER, of Sonora, in the county of Tuolumne, and State of California, have invented a new and improved Washing-Machine; and I do hereby declare that the following is a full, clear, and exact description thereof, which will enable others skilled in the art to make and use the same, reference being had to the accompanying drawing, forming part of this specification.

This invention relates to improvements in machines for washing clothes, having for its object to provide a simple, cheap, and efficient apparatus.

It consists in an enlargement of a grooved rotating cylinder in a suitable tube and operating-mechanism.

The drawing represents a side elevation of my improved machine, a part being broken out.

Similar letters of reference indicate corresponding parts.

A represents a cylinder, which I prefer to make hollow, and of sheet-metal, with a grooved periphery, and having longitudinal slots at the salient angles of the grooves.

This cylinder is mounted on horizontal journals, in a casing or tub, B, also made of metal, one of the said journals being provided with a pinion, C, into which a sector-wheel, D, works, which is attached in suitable bearings at the side of the tub, and provided with

a handle, E, whereby vibratory motion is imparted to it, and from it to the cylinder, through the wheel C.

The clothes are placed within the cylinder, through a door, F, in the face thereof, hinged, and securely hooked when closed.

They are thus moved from side to side over the grooved shell of the cylinder, and a gentle rubbing action imparted to them, the water rising in the cylinder sufficiently to immerse the clothes.

I propose to attach a fire-place, G, at the bottom of the tub, for heating the water therein, which may be made of double walls, H I, to cause a circulation of water through the space, between the said double walls.

A slot, R, is arranged in the side of the tub, for the ready insertion or removal of the cylinder when required.

Having thus described my invention,

What I claim as new, and desire to secure by Letters Patent, is—

The heater G, and the grooved, hollow, and slotted cylinder A, arranged in the tub B, and provided with the operating-wheels C D, and hand-lever E, all substantially as specified.

Witnesses: HERRMANN CRAMER.

GUSTAV S. REUTER,

TRUMAN CRASSETT.
